Fig. 1

Fig. 3

Fig. 1 is a front perspective view of an instrument case, showing my new design;

Fig. 2 is a rear elevational view thereof; and

Fig. 3 is a perspective view similar to Fig. 1 but with the cover section of the case in an open position.

The characteristic features of my design reside in the portions shown in full lines in the drawing.

I claim:

The ornamental design for an instrument case, substantially as shown and described.
